M. J. JACOBS

PENNANT

Filed April 16, 1923

WITNESS:

H. Sherburne,

INVENTOR.
Manuel J. Jacobs
BY *White Post & Evans*
his ATTORNEYS.

UNITED STATES PATENT OFFICE

MANUEL J. JACOBS, OF SAN FRANCISCO, CALIFORNIA.

PENNANT.

Application filed April 16, 1923. Serial No. 632,190.

My invention relates to pennants, banners, flags and similar articles and one of the objects of the invention is the provision of a pennant or like article composed of two or more pieces secured together in edge-to-edge relation without lapping. Another object of the invention is the provision of an article of the character described in which letters or other insignia appear in the body of the article without being superposed thereon so that the letter or insignia is visible from either side of the pennant which is of but one thickness throughout.

My invention possesses other objects and features of advantage, some of which, with the foregoing, will be set forth in the following description of my invention. It is to be understood that I do not limit myself to the showing made by the said description, as I may adopt variant forms of my invention within the scope of the claims.

Referring to the drawings:

Fig. 1 and Fig. 2 are elevations of pennants made in accordance with my invention.

Fig. 3 is a detail on an enlarged scale showing the preferred method of fastening the pieces of the pennants together.

Fig. 4 is a perspective view of a pile, comprising layers of two colors of material out of which the pennant is to be made. The figure shows the pile of layers after the first cuts have been taken, which determine the shape of the pennant.

For the sake of brevity and clearness the word pennant will be used throughout the description and claims to indicate the complete article and will be understood to include banners, flags, mottoes and all other articles of similar character and purpose.

In making pennants it is the custom to use materials of two or more contrasting colors, one to form the field or body of the pennant and the other to form a design or insignia exhibited on the pennant. As ordinarily made, the design is superposed on the unbroken surface of the field or body, and attached thereto by sewing. This of course involves a double thickness of material and the design or insignia is visible only from one side of the pennant. When the body of the pennant is made of two or more pieces, as frequently is the case, a seam with double thickness marks the union of the various pieces. This is objectionable both from the view point of appearance and

because the flexibility of the pennant is not uniform on account of the stiffness at the seams.

In accordance with my invention I cut thru the field or body of the pennant an aperture of the exact size and shape of the design with which it is desired to ornament the pennant. The design is also accurately cut in the desired material and the piece inserted flush in the aperture. I then secure the abutting edges of design piece and body together preferably by means of a zigzag stitch. There is thus no seam or double thickness and the pennant with its inserted design is in all respects of flexibility and appearance, the same as though made of a single thickness of material. Furthermore, the design is visible from both sides of the pennant although of course in reverse on one side.

My method of forming a pennant also has the additional advantage that when two colors are used, two complete pennants, with the position of colors reversed, may be made from one piece of material of each of the colors of the finished size of the pennant. There is therefore a large saving of material in making pennants by my method.

It is also apparent that the method used lends itself to the combination of contrasting colors where there is no inserted design, such as the manufacture of caps, having segments of contrasting colors, and the making of pennants of two or more sections not inserted one within the other. It may also be used for the insertion of designs composed of one or more contrasting colors in clothing of another color to give the effect ordinarily obtained by appliquéd work, but using the minimum amount of material and having nowhere more than one thickness of material.

In practicing my invention to produce the pennants illustrated, for example in Figs. 1 and 2 of the drawings which are formed of blue and gold felt with the letter C displayed thereon, a piece of blue and a piece of gold felt are superposed, one on the other. Two or any other number of pieces may be used but there should be an equal number of each color. Then with suitable means, well known to those engaged in the industry, the complete outline of the pennant is cut thru all of the superposed layers simultaneously, as indicated in Fig. 4. That is to say, the cut is made along the lines 2,

3 and 4, Fig. 4. Next the line 6 is cut and finally the outline 7 of the insignia or letter.

The pieces are then separated from the pile in which they lie and reassembled, a

5 blue point 9 being assembled with a wide gold portion 11, in the latter of which is also inserted the blue insignia 12, as shown in Fig. 1. The gold points 13 are then assembled with the blue portions 14, in
10 which the gold insignia 15 is inserted, as shown in Fig. 2. The assembled pieces form an edge-to-edge contact, that is, the edges abut together and the surfaces are flush with nowhere a double thickness of material. Since the pieces are cut together a perfect match or fit results. Any suitable
15 means may be adopted for securing the abutting edges, but I prefer to secure them by means of a double zigzag stitch shown in
20 Fig. 3, one stitch 16 being formed of blue thread and lying mainly on the blue material, the work being done so that the needle carrying the blue thread pierces the very edge of the material of the other color. In
25 the same manner the second stitch 17, lying mainly on the gold material, is of that color, and extends over into the blue material just enough to secure a hold therein. The
30 stitch so formed is not only very attractive in appearance when viewed closely, but merges with the background colors so completely that at a distance of a few feet is indistinguishable from the base colors.

Reduced to simple terms, it will be seen
35 that with two pieces of material, each the size of the finished pennant, two complete pennants may be made, each composed of the combination of the desired colors and each having an insignia inserted therein,
40 there being absolutely no waste.

It will be appreciated of course that the superposed layers of material need not be cut together but each color may be worked up separately if suitable equipment is at
45 hand to assure accuracy in the cutting. There is, however, an undoubted advantage in cutting the material together since errors compensate themselves when the parts are assembled, and the cost of manufacture is
50 undoubtedly less by this method. It is also, of course, immaterial what form of stitch is used for fastening the design in the field,

provided that the result is neat, and that the edges of the design and field are flatly and securely fastened together.

55

I claim:

1. A pennant comprising a main body of fabric, having an aperture therethru, an insert of size and shape complementary to said aperture disposed flush therein, and a
60 double row of zigzag stitches across the abutting edges of insert and body, one row disposed mainly on the body and close to the edge of the insert and the other row disposed mainly on the insert and close to
65 the edge of the body, each of said rows matching in color the piece on which it mainly lies.

2. A method of making two pennants, one having a body of one color and an insignia
70 of another color and a second pennant having a body of the same color as the insignia of the first named pennant and an insignia of the same color as the body of the first named pennant which comprises superposing two pieces of material of the desired colors, severing the superposed pieces in unison in accordance with a pattern, assembling the severed pieces to form the two pennants and securing the assembled pieces by sew-
75
80 ing.

3. The method of making a pennant having a body of one color and insignia of another color which comprises superposing pieces of material of the desired colors and
85 severing the superposed layers in accordance with the pattern of the insignia, assembling pieces of one color with complementary pieces of the other color and securing the
90 abutting edges of the assembled pieces by sewing.

4. A pennant comprising a plurality of pieces of different colored fabrics arranged in flush edge-to-edge relation, and a double zig-zag stitch joining said flush edges, said
95 stitch being formed with threads of colors corresponding to the colors of the joined fabrics, the stitch of each color of thread lying mainly on the corresponding color of fabric.

100 In testimony whereof, I have hereunto set my hand.

MANUEL J. JACOBS.
